UNITED STATES PATENT OFFICE.

BIRGER LJUNGSTRÖM, OF STOCKHOLM, SWEDEN, ASSIGNOR TO AKTIEBOLAGET LJUNGSTRÖMS ANGTURBIN, OF LILJEHOLMEN, SWEDEN.

STEAM-TURBINE.

1,067,356.

Specification of Letters Patent. Patented July 15, 1913

Application filed March 26, 1913. Serial No. 756,879

To all whom it may concern:

Be it known that I, BIRGER LJUNGSTRÖM,
a subject of the King of Sweden, and a citizen of Sweden, residing at 18 Grefmagni-
gatan, Stockholm, in the Kingdom of Sweden, have invented certain new and useful Improvements in Steam-Turbines, of which the following is a specification.

In steam turbines, especially radial turbines, where the steam is admitted through chambers, arranged in the turbine casing, laterally to the rotating disks, or in radial steam turbines, where the turbine casing is arranged within a mantle, there arises a disadvantage, consisting in the chambers, the turbine casing and the mantle having respectively different temperatures during operation, causing dangerous strains in the said parts at the starting and during the operation of the turbine. Such strains may even cause a displacement of the chambers and the turbine casing, or between the turbine casing and the surrounding mantle with respect to their relative positions, whereby the action of the tightening parts is impaired.

is impaired.

The present invention relates to a device, which has for its object to avoid the said disadvantage. According to the invention 30 this is attained by the chambers being provided within the turbine casing and the turbine casing being provided within the mantle with radial guides in such a way, that a free radial expansion of the chambers 35 with respect to the turbine casing is allowed. This solution of the problem can be effected in different ways. It is preferred, however, to combine the two parts to be connected by means of devices, which 40 are radially movable in the one or other of the connected parts or in both, or which are pivotally or by means of links connected with these parts.

On the accompanying drawings some embodiments of the invention are shown.

Figure 1 represents a longitudinal vertical section of an embodiment of my invention, approximately in a central plane parallel to the sides of the steam chambers; Fig. 2, a plan view of the same on a larger scale, the upper part of the mantle being omitted and the lower part broken away; Fig. 3, a plan view of the turbine-casing without its upper section and without the mantle, the two steam chambers being sec- 50

110

casing or both and permitting the free radial expansion of the said casing without loss of its concentric position. In like manner, similar radial guides e' are interposed between each of the two steam-chambers and the said casing, fitting into recesses at each end as above explained and permitting the radial expansion of said chambers without loss of position or dislodging any part. In order that the exhaust tube g also may be permitted to expand freely such adial

tioned on approximately the horizontal plane of their centers; Fig. 4, a vertical section through a diffuser having this invention applied thereto, the casing and intervening guides being shown as in Figs. 1 and 3; and Fig. 5 represents in side elevation a modification using a different form of guide between the turbine-casing and a steam chamber or diffuser contained therein.

The mantle *a* and turbine-casing *b* within the same are each in two separable sections, upper and lower. The bearings *c* are integral. 65

It will be observed that the sectional view shown in Fig. 1 necessarily cuts off one of the two steam chambers; consequently only the other steam chamber appears therein, with its guide e' , with the mantle a . In the turbine casing b the two parallel steam chambers d are inserted. The turbine shafts, which rotate in opposite directions, and the movable parts of the turbine are not shown. It is clear, that during the operation of the turbine the chambers d become heated approximately to the temperature of the high pressure steam, while the turbine casing will get about the same temperature as the exhaust steam. The mantle a , which is not surrounded by the steam, is heated to the lowest temperature. As the bearings c are secured in the mantle a , it is of course of great importance, that the turbine casing b and the chambers d maintain their central position with respect to these bearings c and to the mantle a . 70 75 80 85 90

to these bearings *c* and to the mantle *a*. 90
To insure this maintenance of proper position
the mantle *a* and casing *b* are provided
at corresponding points of their opposed
faces with recesses which receive the ends
of short guide-rods or guide-bars *e*, which 95
connect the said mantle and casing together
and hold them in proper positions, said
guides being radially movable in said re-
cesses with respect to the said mantle or
casing or both and permitting the free
radial expansion of the said casing without
loss of its concentric position. In like man-
ner, similar radial guides *e'* are interposed
between each of the two steam-chambers
and the said casing, fitting into recesses at 100
each end as above explained and permitting
the radial expansion of said chambers with-
out loss of position or dislodging any part.
In order that the exhaust tube *g* also may
be permitted to expand freely such adial 110

guides *f* are arranged between *g* and *a*. According to Fig. 4 a diffuser *h* is secured in the turbine casing in the same way and provided with the guides *e'* set into recesses of said diffuser and casing and permitting radial expansion of the former without displacement.

The modification illustrated in Fig. 5 substitutes pivoted links *i* for guides *e'* above described, each of these links being pivoted at its ends to lugs on the periphery of a steam chamber or diffuser and the inner face of the turbine-casing respectively. These links obviously permit the expansion 15 without displacement of the steam chamber or other parts to which their inner ends are attached. The guides *e*, *e'*, *f* or *i* are arranged at intervals of ninety degrees around the common center of the mantle 20 casing and steam chambers, two of the guides *e* being located in the meeting line or joint of the two separable sections of the mantle and the corresponding two guides *e'* of each steam chamber *d* being similarly 25 located in the meeting line or joint of the two sections of said casing. This construction and arrangement of parts permits the upper section or cover of the mantle and that of the casing to be removed without 30 injury to the guides or other parts or any inconvenience. However, especially when the guides are made detachable or removable, three, five or more guiding organs can also be employed.

35 Having now described my invention what I claim and desire to protect by Letters Patent is:—

1. Two concentric fixed parts of a turbine

structure having opposed recesses, in combination with guides fitting in said recesses 40 and movable with respect to one of said parts in order that the inner part may expand without its displacement.

2. A turbine-casing and mantle inclosing the same, having opposed recesses, which 45 receive radial guides, permitting the expansion of said casing without its displacement.

3. A turbine-casing and steam chamber inclosed therein having opposing recesses 50 which receive radial guides permitting the expansion of the steam chamber without its displacement.

4. In combination with a mantle consisting of two separable sections and an inclosed turbine-casing, guides arranged between said parts at intervals of ninety degrees and yieldingly connecting them, two of said guides being arranged in the joint of the said two sections in order that one 55 of said sections may be readily removed.

5. In combination with a turbine-casing in two separable sections and a concentric part within the same, radial intervening guides arranged at intervals of ninety degrees and making connection between said part and said casing, two of these guides being arranged in the joint of said casing 65 sections to permit the removal of one of said sections substantially as described.

In testimony whereof I have affixed my 70 signature in presence of two witnesses.

BIRGER LJUNGSTRÖM.
